SELECTIVE CONTROL DEVICE

Richard T. Fox and Vernon I. Hullett, Louisville, Ky.

Application May 15, 1934, Serial No. 725,790

9 Claims. (Cl. 250—20)

The present invention relating as indicated to a selective control device, is more particularly directed to a means for controlling a series of circuits in a pre-arranged manner, both as to the particular circuit and the period of time that such circuit is controlled. It is to be distinctly understood that the device is not limited to use in conjunction with a radio receiving set and that a radio receiving system is used merely as an example of one way in which the present invention may be used.

The invention is especially adapted to operate lighting systems as of an airport or building, and it will control bell signal systems and change electric signs, such as an electrical flashing clock. It is also designed to control a plurality of electrical circuits or furnish a plurality of mechanical impulses on a pre-arranged schedule.

Heretofore radio receiving sets have been operated manually in a manner that requires the attention of an attendant every fifteen or thirty minutes.

The present invention has particular applicability to restaurant usage where it is desired to have a rather lengthy sequence of musical programs. As stated previously, heretofore, in order to receive such programs it has been necessary to tune the set every fifteen or thirty minutes, but this invention is designed to overcome this difficulty and makes it possible to manually set the condenser of a radio receiving set to the desired wave lengths, and at the same time to accurately time the reception so as to receive desired programs. Stated in other words, it is an object of our invention to make it possible to pre-set a radio receiving system so that the condenser will be mechanically actuated for a definite period of time through a desired sequence of programs.

To the accomplishment of the foregoing and related ends, said invention, then, consists of the means hereinafter fully described and particularly pointed out in the claims; the annexed drawings and the following description setting forth in detail certain mechanism exemplifying this invention, such disclosed mechanism constituting, however, but one of various applications of the principle of this invention.

In said annexed drawings:—

Fig. 1 is a front elevation taken immediately behind the panel of a radio set, showing certain parts in section;

Fig. 2 is a side elevation with certain parts in section of the device applied to an ordinary radio set;

Fig. 3 is a detail vertical section through the clutch mechanism for the condenser;

Fig. 4 is a partial section of Fig. 5, taken on line 4—4;

Fig. 5 is an end elevation of the discs 1, shown in Fig. 2;

Fig. 6 is a partial plan view taken from below Fig. 5;

Fig. 7 is a plan view taken from above the brush shaft 27 in Fig. 2;

Fig. 8 is a plan view with parts in section taken on a variable line in Fig. 1;

Fig. 9 is a front elevation of the panel of a radio set embodying the present invention.

The present invention is designed for use with a conventional radio receiving set and is very small and compact. It is placed preferably immediately beneath the condenser of an ordinary radio receiving set. However, the exact location is immaterial and the terms "above" and "below" are used merely as an aid to description and not in any sense as limiting terms. The term "synchronous rotor" is also used in the same sense and is the equivalent of the term "clock" or any clock-like mechanism.

The device is composed of several portions which will be treated under separate headings and mainly consists of means for automatically setting a frequency dial, which shall be termed "automatic frequency dial" for convenience, in a pre-arranged sequence of wave lengths having variable time periods.

Briefly, the device consists of means including a clutch for actuating the condenser of a radio receiving system automatically through a desired sequence of programs. Inasmuch as this result is dependent mainly upon a series of discs, such discs will be first described.

Setting discs

Referring now to Figs. 2, 4, 5, and 6, it will be seen that a plurality of conductive discs 1 are each composed of two substantially semi-circular elements 2 and 3 having their straight edges 4 and 5 bevelled and slightly spaced so as to be in overlapping relation, yet making no electrical contact. These discs preferably have their peripheral edges milled in order to prevent slippage. The semi-circular elements 2 and 3 are assembled upon hubs 6 of insulating material with brass bushings 7 inside and with rings 8 of conductive material around the outside of them, which bushings are in turn loosely journaled in spaced relation upon a shaft 9 as shown in detail in Figs. 4, 5, and 6. At one of the two

peripheral points where the semi-circular elements overlap, a notch 10 is formed by removing material from each element, thus breaking the continuity of the circumference. On a 5 squared shaft 14, parallel to the disc shaft 9, a roller 15 is mounted so as to move longitudinally thereon for registration with the periphery of any of the discs 1 to impart to the latter a rotational movement about the disc axis upon turning 10 of the squared shaft 14 by means of the knob 51 mounted thereon at the front of a suitable panel 48. Parallel to the squared shaft is double spirally grooved rotatable shaft 16 connected through gears D, C, and B with shaft G. 15 This shaft is movable manually since it is provided with a knob 20 at the front of the panel. The shaft 16 carries a travelling nut 17 provided with a fork 22 which engages a grooved circular collar 23 fixed to the roller 15, as shown in Fig. 20 8. Thus, when the double spirally grooved shaft 16 is rotated in one direction its nut 17 moves longitudinally through the length of the grooved portion of the shaft 16, then returns carrying the roller 15 on the squared shaft 14 through a like 25 movement. When the roller comes into registration with the periphery of the desired disc 1, the squared shaft 14 is then rotated to move that disc through a desired angle. Thus, the discs 1 may all have their positions adjusted in a 30 like manner from an empirically selected neutral or starting position, which, in this case, is the vertical disposition of the line of separation of the semi-circular elements 2 and 3.

Mounted so as to engage with the notches 10, 35 formed in the discs 1 when they are neutrally disposed, is a travelling brush 25 carried by a nut 26 on a threaded shaft 27, which shaft is rotated as a function of time, as shown in Figs. 2 and 7. The nut also slidably travels along shaft 27a 40 which prevents rotation thereof. When the discs are in any but neutral position, the travelling brush 25 electrically engages one of the semi-circular elements 2 or 3, each disc 1 having one segment always electrically connected with the 45 disc shaft 9 and the other segment with a collector ring 8 and a stationary brush 28. Brushes 28 are set with enough pressure on rings 8 to prevent any disc being moved by friction between it and adjacent discs. The manual setting assembly, namely, the double spirally grooved shaft 16 and the squared shaft 14 for predetermining time and angular displacement respectively, has a counterpart for reversing these movements, termed for convenience, threaded power shaft, 50 and squared power shaft (see Fig. 8). The threaded power shaft 29 carries a travelling nut 36 which is provided with a bifurcated element 37 for engagement with a roller 38, mounted for longitudinal movement on the squared power 55 shaft 30. The threaded power shaft 29, as well as the travelling brush shaft 27, is driven by a synchronously operating rotor 35, imparting uniform longitudinal motion to the power roller 38 and to the travelling brush 25. Thus the roller 60 38 and brush 25 simultaneously and sequentially engage the various discs 1 so that when the brush 25 completes a circuit through one of the semi-circular elements 2 or 3 to a reversible motor 39 mounted on the squared power shaft 65 30, the power roller 38 is rotated, and correspondingly rotates the particular disc 1, until the notch 10 arrives opposite the travelling brush 25 and the motor circuit is broken.

The driving means for simultaneously actuating 70 the shafts 27 and 29 comprise a synchronous 75

rotor 35 which may be of conventional design and need not be shown in detail. The casing for such rotor is designated 35 and in order to avoid confusion the mechanism within the casing is not shown.

A shaft 55 driven by means within the casing 5 35 projects rearwardly therefrom, as shown in Fig. 2, and has mounted thereon a pinion 33 meshing with large gear 32 that in turn meshes with the small gear 31 mounted upon shaft 27, 10 and the small gear E on shaft 29, thereby producing uniform movement of both shafts 27 and 29.

Travelling brush

The travelling brush shown in detail in Figs. 2 and 7 is composed of a travelling nut 26 with arm 11 insulated from it and extending downwardly, hinged on a pin perpendicular to the direction of travel so that it may swing through a small arc in the plane of direction of travel. It is centered vertically downward by a spring (not shown). This arm 11 is of proper dimension to contact the discs 1 when their notches 10 are moved from the neutral position and to slip through their notches when in neutral position. Projecting from this arm at its hinge, at an angle of slightly less than 90°, are two arms 12 and 13. When the vertical arm 11 comes in contact with the side of a disc 1 it is caused to 20 lag behind its center position, thus pushing one of the two arms 12 or 13 upward against one of two spring contacts 18 and 19 in the travelling nut 26. This completes an electrical circuit between the disc 1 and the travelling nut 26, thence 25 through shaft 27 to power. The spring contacts 18 and 19 are adjustable so that contact is completed just when the center of the hinge of the vertical arm 11 is over the center of the disc 1, travelling either way.

The motor 39 has two sets of field coils for reversing rotation, one set being connected to one group of semi-circular elements through slip rings 8 and brushes 28, the other set being connected to the other group through the disc shaft 9. The travelling brush 25 is common to both field windings as it engages only one semi-circular element for any one setting. It is to be understood that means other than a motor may be used and that the particular drive from the motor to the various shafts may be changed for equivalent devices.

Pre-setting means

When the device is used to control the operation of a radio receiving set the condenser shaft 40 of the receiving set is releasably geared to the squared power shaft 30 and receives an angular adjustment proportional and in reverse direction to that of the discs 1. A frequency dial 21 marked in duplicate to the dial 41 on the receiving set 55 has teeth on its 180°, opposite the half, on which frequencies are marked, and is geared to the squared setting shaft 14 as shown in Fig. 1, and receives angular adjustments proportional to that of the discs 1 in setting. Having teeth on part 60 of the periphery of dial 21 prevents notches in discs 1 being turned more than 177° from their neutral positions. Another dial 42, marked with equally spaced numerals from one up to the number of discs used and with an extra suitable space marked between the highest number and one, is connected through the medium of what is termed a Geneva movement, that is slots 43 are 65 engaged by the finger on plate 44. Shaft G 70 may be rotated manually by means of a knob 20, 75

and the small gear B on such shaft rotates small gear A which is fixed on shaft K to which plate 44 is also attached. Likewise, gear C, mounted upon stub shaft H, is rotated inasmuch as it meshes with B and then C rotates shaft 16 by means of D. Thus, every time the shaft G receives an impulse the setting roller 15 is moved to engage the next disc 1. As the setting mechanism operates from opposite ends of the device 10 each successive whole operation while the double spirally grooved shaft 16 is always turned in the same direction, this numbered dial 42 indicates which disc 1 is engaged, counting them from the end at which setting started. The extra space 15 between the highest and lowest numerals is provided so that the double spirally grooved shaft may be turned enough after the highest number shows to bring the setting roller out past the last disc after setting, allow for lost motion at 20 the end of the double-spiral groove, and bring the setting roller back in contact with the disc when the number "one" shows. Two time dials 52 and 53, one to indicate the hour and the other fifteen-minute intervals, respectively, are geared 25 in the proper relation to each other and friction driven with the proper relation from the disc indicator dial 42 above described. They are provided with a manual setting knob 54, mounted upon shaft 57, and, in setting, after the disc indicator dial 42 has been brought to its number 30 one position, they may be set to the time at which a desired sequence of programs is to start, so that thereafter they will indicate the time being set for.

35 Movement of the dials 52 and 53 is obtained through the medium of friction wheel 50 that peripherally engages the inner annular surface 56 on dial 42. The friction wheel 50 is fixed upon shaft 57, and the gear 58 is likewise fixed upon 40 this shaft. Movement of gear 58 is translated into movement of hour time dial 52 through gear teeth, as shown in Fig. 1, and at the same time movement of fifteen minute time dial 53 is obtained through pinion 60 on shaft 71, which shaft has small gear 59 mounted thereon in mesh with the teeth of disc 53. Thus, it will be seen that as the dial 42 rotates, the time dials 52 and 53 are correspondingly rotated.

The dial 61, Fig. 7, of 180° arc marked with 50 proper spaces from zero at its middle upward toward each end, has one end connected to a rod 62 in turn connected to the ends of two levers 63 and 64, one near each end of the device pivoted so that their opposite ends 65 and 66 lie in the path of the travelling brush nut 26 as it 55 nears the end of any operation in either direction. This dial 61 is held at its zero position by a spring 67 and the levers 63 and 64 are so placed that as the travelling brush passes the contact point at which the last disc on either end is operated it will begin to displace one of the levers turning the dial 61 to indicate how many minutes must elapse before the synchronous rotor 35 would bring the travelling brush 25 backward to that same point when the rotor is started in the 60 opposite direction. Also, marked on each side of the zero point of this half-dial 61 is a curved arrow, as shown in Figs. 1, 2, and 9, which indicates in which direction the starting knob 65 should be turned to start the rotor for the next 70 operation of the device. Since the direction of travel of the travelling brush 25 and power roller 38 depends on which way the synchronous rotor 38 is started these curved arrows and the double spirally grooved setting shaft 16 with its disc

75 indicator dial 42 provide means for utilizing the device from either end, all discs having been realigned in their zero position during the preceding operation. It is not necessary to know in which direction the device is being operated.

5 A double throw single contact switch 68, similar to a telephone switch, in the power supply source of the synchronous rotor 35 has its lever 69 located with respect to the rod 62 that transmits the motion between the levers 63 and 64 in 10 the path of the travelling brush nut 26 and half dial 61, so that when the travelling brush nut 26 reaches a suitable point near either end of the threaded shaft 27 on which it moves, the circuit through the synchronous rotor will be 15 broken and the device stopped. This switch does not affect the operation of the radio set.

The position of the travelling brush 25 in 20 terms of time until the next operation will start is then indicated on the half dial 61. This position may be adjusted and the device thus set to begin operation after a certain elapsed time by turning the synchronous rotor through its manual starting knob 70 or other knob geared thereto.

Condenser control

The motion of the square power shaft 30 is applied to the condenser shaft 40 of the receiving set by a reversely geared connection, such as 30 gear 77, pinion 78, shaft 79, pinion 80 and gear 81. Such gearing is shown in Figs. 1, 2, and 8, as extending through the synchronous rotor casing 35, but it will be understood that it acts independently and may, if desired, be brought 35 around such casing. The arrangement as shown merely affords a more compact device.

A special type dial including a clutch, provides 40 for disconnection and independent operation of the receiving set from the device at this point. This clutch, as seen in Fig. 3, consists of two discs 82 and 41, one (41) being fastened tightly to the condenser shaft 40, the other (82) being connected with the gear 81 by a sleeve integral therewith having a projection 84, said sleeve being 45 loosely journalled on the condenser shaft, and said projection being received in a slot 85 in sleeve 86 connected to gear 81. The rectilinear position of the driving gear is fixed; the jointed sleeve permits the rectilinear position of the adjacent disc 82 to be changed without breaking its connection with gear 81. A coiled spring 87 on the sleeve presses the rubber face 83 of the movable disc 82 against the axially 50 fixed disc 41. A shaft 88 projecting through the panel 15 ending in a suitable knob 89 outside and a ball bearing 90 in the end resting against the movable disc 82 operates against this spring to 55 separate the discs 82 and 41. Rotational motion of the knob is translated into axial motion of the shaft when the frequency dial 41 is mounted parallel to the panel 15. If the frequency dial is placed perpendicular to the panel, the same shaft may terminate in an eccentric pin working 60 in a grooved collar at the disc end of the coiled spring. With the former placing of the dial, the shaft 88 projects through an arcuately shaped hole 91 in the fixed disc or dial 41, such hole being disposed around its shaft through an arc 65 long enough to permit 180° turning of the condenser shaft and dial. The knob 89 is appropriately marked, as shown in Fig. 9, to indicate regular or automatic tuning. When the discs 82 and 41 are pressed together, the automatic de- 70

vice tunes the set, when they are apart, as shown in Fig. 3, it can be tuned manually.

The movable disc 82 is slightly smaller in diameter than the axially fixed disc 41. This provides clearance and the axially fixed disc 41 has a short pin 97 perpendicularly mounted to the face of such disc. A toggle switch 98, Fig. 1, parallel with the master switch of the receiving set, has its lever 99 ending in a fork 100, one side longer than the other, so disposed near the edge of the disc 41 that the pin 97 in passing will catch in the fork 100 and throw the switch to its off position, when the pin will be between the forks of the switch so that when the disc is turned in the opposite direction the switch will be turned on. The switch 98 and pin 97 should be so disposed that this occurs preferably near one end of the 180° through which the frequency dial and condensers operate. Sufficient space should be marked with the word "off" on the frequency scale to provide for the operation of this switch. By eliminating stops from condensers and gearing dials 21 and 41 with proper ratio to discs 1, it is possible to provide for tuning to full 180° . The pin 97 and the word "off" will then be placed past the end of the frequency scale.

Operation

30 Suppose that it is desired to bring in the following succession of programs: 5:30 to 6:15—WLW; 6:15 to 6:30—silent; 6:30 to 6:45—WSM; 6:45 to 7:00—silent; 7:00 to 7:30—WTAM; 7:30 to 8:00—WHAS; 8:00 to 8:30—WMAQ. The master switch of the receiving set is turned off and the clutch knob 89 is turned to "automatic". Suppose that the frequency dials 21 and 41 are marked off in kilocycles from left to right and that the dial 41 is now at 900 kc. Set the automatic frequency dial 21 to the same setting, turn the automatic time set knob 20 until the numeral "one" appears on the disk indicator dial 42, and while holding knob 20 turn the time dials 52 and 53 to indicate 5:30. Turn the automatic frequency knob 51 until 700 kc. appears on the automatic frequency dial 21. This adjusts the first disc 1 from its neutral position counter-clockwise through a proportionate angle. Then turn the time set knob 54 until 6:15 appears on the time dials. Turn the automatic frequency knob 51, moving the automatic frequency dial 21 clockwise to the limit of its rotation, where "off" appears. This adjusts the fourth disc from its neutral position clockwise through a proportionate angle. Turn the time set knob 54 until 6:30 appears on the time dials 52 and 53 and turn the automatic frequency knob 51 until 650 appears on the automatic frequency dial. This adjusts the fifth disc 1 from its neutral position counter-clockwise through a proportionate angle. Turn the time set knob until 6:45 appears on the dials and turn the automatic frequency knob until "off" appears on the automatic frequency dial. This adjusts the sixth disc from its neutral position clockwise through a proportionate angle. Setting for the rest of the programs continues in like manner until all available discs have been used and the letter X appears on the disc indicator dial 42. Assuming, for example, that it is now 5:21 and as the first program is to start in nine minutes turn the synchronous rotor starter 70 until the figure "9" appears on the start indicator dial 61, then give the starter a twirl in the direction indicated on that dial.

The operation of the device will now be followed.

Although the master switch of the radio receiving apparatus has been turned off the switch 98 operated by the dial 41, connected in parallel, is on as long as this dial indicates a frequency. The apparatus, therefore, continues to operate at its setting of 900 kc. If it is desired that the apparatus be silent until 5:30, both frequency dials 41 and 21 are turned to the "off" position, and the radio set will turn on automatically when the first program is selected.

The synchronous rotor 35 turns the two threaded shafts 27 and 29 until at 5:30 the travelling brush 25 and the power roller 38 simultaneously reach the "operation point" of the first disc 1. This is when the hinge of the brush arm is directly above the center of the first disc 1. An electrical circuit is completed through the travelling brush 25, the right half of the disc 1, the stationary brush 28 tapping it, and field coil "B" of the reversible motor 39. The power roller 38 is thus caused to rotate and correspondingly rotates the particular disc 1 clockwise through an angle equal to its adjustment in setting, and the condenser shaft 40 receives a proportionate angular adjustment counter-clockwise.

This is what has happened.—the dials 21 and 41 having originally been set at 900 kc., the first disc 1 was adjusted counter-clockwise through an angle proportionate to the difference on the dials between 900 kc. and 700 kc. The power roller 38 now reverses that adjustment but gives an adjustment to the condenser shaft 40 identical in angle and direction to that of the setting through reverse gears.

When the notch 10 of the first disc 1 coincides with the arm 25 of the travelling brush the arm of the brush drops into it and the circuit is broken. The travelling brush 25 and power roller 38 move on to the left as viewed in Fig. 2. As the second and third discs were left in their neutral positions the arm of the brush passes through their notches without completing a circuit. When the brush 25 and roller 38 reach the operating point of the fourth disc at 6:15 a circuit is completed through the brush 25, the left side of the disc, the disc shaft 9, and field coil "A" of the motor 39. The power roller 38 reverses the adjustment given to the disc in setting, as above, turning it through an angle proportionate and with opposite direction to the difference on the dials between 700 and "off". This adjusts the condenser shaft 40 through an angle identical in degree and direction to that through which the automatic frequency dial 21 and the fourth disc were adjusted in setting. This causes the pin 97 on the frequency dial 41 to operate the automatic switch 98, turning off the set. The fourth disc 1 is returned to its zero position, the brush arm 25 falls into the notch 10 and the brush and power roller 38 move on until at 6:30 they reach the operation point of the fifth disc. (The distance between operation points of two adjacent discs is called an "interval" and the travelling brush and power roller traverse an interval in exactly fifteen minutes.) The condenser shaft 40 now receives an adjustment identical in direction and degree to the difference on the dials between "off" and 650. This was the same adjustment given to the automatic frequency dial 21, and fifth disc in setting.

Suppose that it is now wished to interrupt the predetermined sequence of frequencies for some

other frequency later decided upon. Turn the clutch knob 89 to "regular" and tune the set as desired. If a frequency that lies in a portion of the dial mark "off" is desired, turn on the master switch of the radio set. (This operation can be combined with that of the clutch knob.) To resume the prearranged sequence turn the frequency dial 41 of the set to the frequency arranged for at that time and turn the clutch knob 89 to "automatic".

The travelling brush 25 and roller 38 move on through a complete operation, adjusting the condenser shaft as described above, and bring all discs back to their neutral positions. At the end of the operation the travelling brush presses against the lever 65, causing the half-dial 61 to be displaced from its zero position. This continues until the rod 62 of the start indicator is moved far enough to move the toggle arm 69 of the double throw switch 68 from its central "on" position, when the circuit through the synchronous rotor 35 is broken and the device stops. The receiving set is left in the status achieved by the last disc. Obviously, this can be "off" if desired. In combination with a cam or combination of cams the device will operate lighting systems as of an airport or building; will control bell signal systems; will change electric signs as of an electric flashing clock; will control a plurality of electrical circuits or furnish a plurality of mechanical impulses on a pre-arranged schedule. The length of the interval in time may be varied.

Variations

A variation of the device is formed by governing the power supply so that the square power shaft and the power roller are driven at constant speed. The degree through which the discs are displaced from their neutral position will then supply the time element and the direction of displacement will supply a choice between circuits. The synchronously operating rotor is eliminated and for it is substituted either (a) a constant pressure as that given by a spring forcing a brush of solid construction to pass through the notches in the discs as they are returned to their neutral positions by the power roller (which is moved simultaneously with the brush), or (b) a spring-opposed electro-magnet on each end of the assembly to operate alternately on whole successive operations of the device, pulling the travelling brush and power roller towards them through one interval each time the circuit is broken by the turning of a notch to zero position.

This variation permits greater flexibility in the period of time any electrical circuit is held closed but sacrifices the degree of individual setting. The latter can be supplied outside the device by means of rheostats or by combination with the device as described in the first part.

1. If the surface of the shaft on which the discs are assembled is built up of insulated segments, each tapped, and the stationary brushes are tapped, a choice will be afforded between a plurality of circuits each time the stationary brush and power roller engage a disc, and the same circuit will be kept until the power roller, now time controlled, returns the disc to its neutral position. These taps from each disc can be made available to a plurality of jacks, each part of the circuit or circuits to be controlled.

2. If the choice desired is between timed operation of only two circuits, or elements, the circuits between the stationary brushes and field

coil "B" of the motor and between the disc shaft and field coil "A" of the motor can be used.

Under application (1) this variation can be used to control either by direct electrical contact a moving object such as a robot, a ship, an airplane, a torpedo, directing it through a planned maneuver. In conjunction with radio remote control it can be made to control a group of such units, putting them through a planned maneuver, permitting exact charting and planning of a contemplated movement based on calculations of speed and drift with allowance for influence of external forces. It can also be made to control bell signal systems, airport or plant lighting systems, or any multiplicity of electrical circuits.

Under application (2) this variation is especially adaptable to the operation of safe combinations, as in the opening of a number of safes in branch banks from a central point.

Conclusion

It will now be seen that the present device when applied to a radio receiving set will automatically complete the power supply source to the set and will tune the set to predetermined frequencies or turn it off or on all at predetermined times. That the setting of the device to accomplish this purpose requires no more time than would be consumed in setting the apparatus in the ordinary way. That the setting of this device is accomplished by turning knobs outside the panel of the set without the necessity of getting inside to adjust complicated mechanism, and that this setting is a simple combination as of an ordinary radio receiving apparatus in conjunction with a clock. That it requires less skill and effort in use than any other existing device that will accomplish the same purpose. That it is simpler and cheaper in construction and easier to maintain than any other such device. That it can be attached to any radio receiving set merely by substituting its special type dial for the orthodox dial on the condenser shaft of the radio set. That in order to accomplish its purpose it does not change or tap in any way the electrical circuits within the radio set (it may use current from the set to light its dials as is customary in orthodox radio sets.) That it takes up a smaller amount of space per unit of time over which it will function than any other such device. That the length of time over which it will function is limited only by the number of discs, additional discs and stationary brushes and a lengthening of the longitudinal parts being all that is necessary to increase the time of operation. That after each operation it is ready without preliminary adjustment, to be set for the next operation. That it is not affected by temperature changes. That it will set the condensers at any angle within their normal range of operation, so that the choice of possible frequencies is limited only by the capacities of the set. That it will select such frequencies as have been arranged for with extreme accuracy limited only by the accuracy of the manual setting operation. That after the device has been set and started no further attention is required during the time of its operation. That a radio receiving set to which the device is attached may be operated independently of the device by simply turning a knob. That a pre-arranged program may be interrupted and resumed during the operation of the device. That a single frequency may be held without interruption for any multiple of fifteen minutes within the limits of the device.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said manual means including a double spirally threaded shaft and a square shaft.
2. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said manual means including a double spirally threaded shaft and a square shaft with a roller mounted on said square shaft for engaging the discs in said series of discs in a desired sequence.
3. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said manual means including a double spirally threaded shaft and a square shaft with a roller mounted on said square shaft for sequentially engaging each of said discs in said series of discs.
4. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said manual means including a double spirally threaded shaft and a square shaft with a roller mounted on said square shaft for sequentially engaging each of said discs in said series of discs, and a nut on said double spirally grooved shaft for moving said roller longitudinally.
5. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said manual means including a double spirally threaded shaft and a square shaft with a roller mounted on said square shaft for sequentially engaging each of said discs in said series of discs, and a nut on said double spirally grooved shaft for moving said roller longitudinally.

quence of wave lengths, and means mechanically actuated to tune said system to a corresponding sequence of wave lengths, said mechanical means including a series of discs having peripheral recesses therein, there being manual and power means for rotating said discs, said power means including a threaded shaft and a square shaft with a roller mounted on said square shaft for engaging the discs in said series of discs in a desired sequence.

6. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, there being manual and power means for rotating said discs, said power means including a threaded shaft and a square shaft with a roller mounted on said square shaft for engaging the discs in said series of discs in a desired sequence, and a nut on said threaded shaft for moving said roller longitudinally of said square shaft.

7. In an apparatus of the character described in combination, means for manually tuning a radio receiving system, and mechanical means for tuning said system, said mechanical means including a series of discs supported on a disc shaft, a square manual setting shaft, a spirally grooved shaft, a square power shaft and a threaded shaft, all of said shafts extending substantially parallel to each other.

8. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, and a travelling brush mounted above said discs, said brush being movable upon a member extending transversely to said discs and passing through said recesses during such movement.

9. In apparatus of the character described in combination, a radio receiving system and a tuning mechanism therefor, means manually actuated to time said system to a pre-arranged sequence of wave lengths, and means mechanically actuated to tune said system to a corresponding sequence of wave lengths, said mechanical means including a series of discs having peripheral recesses therein, and a travelling brush mounted above said discs, the path of travel of said brush extending through the peripheral recesses in said discs when such recesses are aligned at the top of said discs, said brush being secured to a screw threaded nut mounted upon a rotatable screw threaded shaft.
